Adel Comeau
ATTORNEY

UNITED STATES PATENT OFFICE

STUART SPEIRS, OF NEW YORK, N. Y., ASSIGNOR TO STUART UTILITIES CORP., OF NEW YORK, N. Y., A CORPORATION OF NEW YORK

RESILIENT BELT

Application filed November 2, 1929. Serial No. 404,437.

This invention relates to a resilient belt, suitable for men or women.

The object of the invention is the production of a belt of great resiliency, and adapted to produce a stretching effect under violent strains without diminishing the substantiating power thereof. The second object of the invention is the production of a resilient belt, with which the usual pressure at the hips of the user is reduced and one that also secures a reduction of pressure under the belt of the buckle. The third object of the invention, is the production of the resilient belt, which can be used with comfort when the user indulges in strenuous exercises, as when rowing, playing tennis, golf, baseball, running, jumping and when indulging in various other athletic exercises. The fourth object of the invention is the production of a resilient belt suitable for a user not having protruding hips, and which will maintain the trousers or other garment supported by the belt at all times in proper position. The fifth object of the invention is the production of a belt, which will support trousers or other garments, without excessive pressure and friction between said belt and the user.

The organization of the invention comprises a strap or body portion of the usual construction of leather, or other suitable material, and to which is detachably and adjustably connected one or a plurality of cushion pads.

In the accompanying drawings Fig. 1 represents a perspective view of the resilient belt; Fig. 2 shows a top plan view of said belt and Fig. 3 is a section of Fig. 2 on the line 3, 3. Fig. 4 shows a fragmentary portion of a modified belt and Fig. 5 is a section of Fig. 4 on the line 5, 5.

The resilient belt which may be of leather or other suitable material is indicated comprising the strap or body portion 20, with the buckle 21 at one end, having the tongue 22 and the openings 23, adjacent to the other end 24 in the usual manner. The usual guide loops 25 extend from the strap 20, for the end 24.

A plurality of female members 30 of snap fasteners extend from and are fastened to

the strap 20. In this instance the said members 30 comprise two pairs in groups of three at portions of the strap 20, which will bear against the sides of the user, and a group of two of said members are located adjacently and to the rear of the buckle of the strap. The number of groups of the fasteners, the number in each group and their locations can be varied.

A pair of similar cushion pads are indicated in their entirieties by the numeral 35. Each of said pads comprises a cover consisting of two members 36 of leather or other suitable material stitched together at their longitudinal edges 37, and at their ends 38, to form a pocket 38a in each pad. At the ends of each pad are formed the clamping flaps 39. Within each of said pockets is located a flexible, elastic or yielding core 40, in this instance of sponge rubber. The said core 40 in this instance is indicated as oval shaped in cross-section, but it may be rectangular, cylindrical or semioval. The ends of said core extend to said clamping flaps. In each of said flaps are secured in this instance three male members 41 of the snap fasteners, and by engaging the members of the snap fasteners, the cushion pads 35 can be adjustably and detachably fastened in place to the strap 20, as it requires only one pair of the fasteners at each end of the cushion pad to hold it in place and consequently the positions of said pads can be varied to different positions of the strap to suit the user.

A third cushion pad is indicated in its entirety by the numeral 45. It comprises a cover consisting of the members 46 similar to 36, stitched together at their longitudinal edges 47 and ends 48, forming a pocket with a flap 49 at one end thereof. A pair of male members 50 of snap fasteners extend from the flap 49 to engage the female members of the snap fasteners behind and adjacent to the buckle 21.

In the modification shown in Figs. 4 and 5 the strap is again shown at 20. A cushion pad 55 comprises a cover of leather or other suitable material consisting of the flat vertical member 56 and the semioval shaped member 57. The said members are stitched to

each other at their longitudinal edges as indicated at 58 and at their ends as indicated at 59 to form a pocket 60. At the ends of each flap are formed clamping flaps 61. Within 5 each pocket 60 is located a flexible, elastic or yielding core 62 in this instance of sponge rubber. In this modification the core is indicated as semioval in cross-section. The ends of the core extend to said clamping flaps. The flaps 61 are stitched to the strap 20 as indicated at 63.

It will be noted that instead of the sponge rubber and like material contained in the pads, inflated tubes similar to the air tubes of automobile tires may be used. It will 15 also be noted that when the pads are worn or destroyed, other pads may be connected to the strap.

Various other modifications may be made 20 in the invention and the present exemplification is to be taken as illustrative and not limitative thereof.

Having described my invention what I desire to secure by Letters Patent and claim is:

25 1. In a belt of the character described the combination of a strap, a plurality of cushion pads located adjacent to the inner face of the strap, each cushion pad comprising a cover forming a pocket with flaps formed at 30 its ends, members of snap fasteners in groups extending from the strap, a group of accompanying members of the snap fasteners extending from each flap of each cushion pad, the coacting members of the fasteners 35 adapted to engage each other to secure said pads in different positions to the strap, and a core of sponge rubber in each pad.

2. In a belt of the character described, the 40 combination of a strap, a plurality of cushion pads located adjacent to the inner face of the strap, flaps formed at the ends of the pads, a plurality of members of snap fasteners extending from the strap, and a plurality of accompanying members of the snap fasteners 45 secured to each of said flaps, the coacting members of the fasteners adapted to engage each other to secure said pads in different positions to the strap.

50 Signed at the borough of Manhattan, city of New York, in the county of New York and State of New York, this 30th day of October A. D. 1929.

STUART SPEIRS.
